UNITED STATES PATENT OFFICE.

GEORGE WASHINGTON WATTS, OF ONEONTA, NEW YORK.

VESSEL CONSTRUCTION.

1,081,876.

Specification of Letters Patent. Patented Dec. 16, 1913.

Application filed June 6, 1913. Serial No. 772,138.

To all whom it may concern:

Be it known that I, GEORGE W. WATTS, a citizen of the United States, residing at Oneonta, in the county of Otsego and State 5 of New York, have invented new and useful Improvements in Vessel Constructions, of which the following is a specification.

This invention relates to vessels such as boats and ships, and particularly to specially 10 constructed propelling mechanism therefor.

In the propulsion of canal boats particularly, it has been found impractical to use self propelling means, due to the fact that the "wash" from the propellers has a very 15 decided tendency toward destroying the side walls of the canal.

It is the object of my invention to overcome this objectionable feature by providing means for preventing the so called 20 "wash" from acting directly against the side walls of the canal.

A further object is to provide means for effectively supporting and preventing vibration of the external portion of the propeller 25 shaft within its concavity in the under side of the boat hull.

With these and other objects in view, the invention consists of certain novel features of construction, combination and arrangement of parts, as will be hereinafter, described and claimed.

In the accompanying drawings:—Figure 1 is a fragmentary side elevation of a ship constructed in accordance with the invention; Fig. 2 is a fragmentary front elevation, showing the propeller shaft in transverse section; Fig. 3 is a side elevation of a portion of the propeller shaft, showing a modified arrangement and combination of 40 propellers; Fig. 4 is a fragmentary side elevation of a further modified form of ship construction; Fig. 5 is a rear elevation of the same; and, Fig. 6 is a transverse sectional view taken therethrough.

Referring to the drawings it will be seen 45 that I have provided in the hull 1 of the ship a longitudinally disposed concavity 2 having rather abrupt side walls 3 and more gradually, inclined front and rear walls 4 and 5, respectively, so that the passage of water longitudinally through the concavity will be inappreciably interrupted, whereas lateral movement of the water therethrough will be prevented. The propeller shaft 6, 50 which extends longitudinally through the ship and is connected to some suitable source

of power (not shown) passes through the front and rear walls 4 and 5 of the concavity and is inclosed at these points by suitable water-tight packing glands 7 and 8, respectively. The ship keel 9 is partially cut away within the concavity 2, the base portion thereof being retained to serve as strengthening means for the ship proper and further has supporting means for the 65 propeller shaft, the exposed portion of which latter is of considerable length and would otherwise be subjected to considerable vibration. Upwardly and outwardly inclined braces 10 are interposed between the 70 remaining portion of the keel 9 and the side walls 3 of the concavity so as to prevent lateral displacement of the said portion of the keel. Vertical bearing members 11 and 12 extend between the portions 75 9 of the keel and the curved top wall 13 of the concavity and are disposed preferably in advance of and in the rear of the propeller wheel 14, which is attached centrally to the propeller shaft 6. These members 11 and 12 are provided with journal boxes 15 and 16, in which the propeller shaft rotates, and suitable oil ducts 17 and 18, respectively, are provided in the upper portion of the bearing members and lead from suitably disposed oil cups (not shown) to said journal boxes 15 and 16, thus providing for the constant lubrication of these bearings which are exposed to the action of the water at all 85 times.

The propeller shaft 6 if so desired may be extended through the stern of the ship's hull, as at 19 in order that an auxiliary propeller 20 may be attached thereto when the occasion demands. This provision is made 95 to provide additional propulsion means to increase the power of the ship when used for navigation through open water.

In Fig. 3 I have shown a plurality of relatively spaced propellers 21 mounted upon 100 a propeller shaft 22 to illustrate an arrangement of propellers which might be desirable. In case a plurality of propellers were provided upon the exposed portion of the propeller shaft within the concavity in the under side of the ship it would be necessary to provide bearing members at convenient intervals between the propellers in order to effectively sustain the shaft and prevent the vibration thereof.

From the foregoing description it will be seen that, upon operation of the propeller

2
5 shaft, the direction of motion of water within the concavity will be almost entirely in a longitudinal direction, lateral impact of the water being resisted by the side walls of the concavity so as to prevent its being directed against the side walls of the canal, through which the boat passes.

10 The structural features of the invention as combined with the provided concavity 10 lend strength to the construction as is necessitated by the general conformation of the concavity.

15 In the remaining figures of the drawing, a further modification is shown, wherein the hull 23 of the vessel is provided medially with a longitudinal channel 24 within which the propellers 25 are mounted upon the longitudinally extending crank shaft 26 journaled in the bearings 27. The connecting rod 28 extends upwardly from its point of connection with the crank shaft 26 through the vertically disposed water-tight casing 29 to its point of attachment to the engine (not shown). Longitudinally extending keels 30 and 31 are disposed at each side of the channel 24 and rudders 32 and 33 are pivotally connected to the rear ends of the said keels. The pivot rods 34 and 35 of the rudders 32 and 33 extend upwardly to a 20 suitable position above the deck where they are provided with cranks 36 and 37. A transversely disposed connecting rod 38 has its extremity pivotally connected to the said crank and a manually operable tiller 39 is 25 shown connected medially to the rod 38, but it is to be understood that any other desired means for operating the companion rudders may be employed.

30 The exhaust pipes 40 of the engine extend longitudinally with respect to the channel 24 and are provided with branch pipes 41 which project into the said channel and have rearwardly projecting discharge nozzles 42 disposed in front of the different propellers 45 for directing the exhaust fluid of the engine against the same. By this means, the exhaust is utilized to assist in the operation of the propellers.

40 As the channel 24 extends throughout the length of the vessel, the longitudinal movement of water through the same will be unobstructed, whereas the keels 30 and 31 will serve as check walls to overcome the lateral "wash," as should be clearly apparent.

55 From the foregoing description taken in connection with the accompanying drawings, it should be apparent that I have provided several modified forms of ship construction whose general features may be em-

bodied in the construction of canal boats 60 and any other form of boats or ships as is found desirable in practice. I desire to have it understood, however, that minor changes in the details of construction falling within the scope of the invention may be resorted to in practice.

Having thus described my invention what I claim is:

1. The combination with a vessel's hull having a longitudinal concavity provided in its under side formed by abrupt side walls and gradually inclined front and rear walls, of a keel extension provided within the concavity in spaced relation to the top wall thereof, means for bracing said keel extension within the concavity, a propeller shaft passing longitudinally through said concavity, means for operating said shaft and a propeller wheel secured to said shaft within the concavity. 76

2. The combination with a vessel's hull having a longitudinal concavity provided in its under side formed by abrupt side walls and gradually inclined front and rear walls, of a keel extension provided within the concavity in spaced relation to the top wall thereof, means for bracing said keel extension within the concavity, a propeller shaft passing longitudinally through said concavity, means for operating said shaft, a propeller wheel secured to said shaft within the concavity, and additional bracing means for said keel extension having journal boxes for the reception of the propeller shaft. 85

3. The combination with a vessel's hull 95 having a longitudinal concavity provided in its under side formed by abrupt side walls and gradually inclined front and rear walls, of a keel extension provided within the concavity in spaced relation to the top wall 100 thereof, means for bracing said keel extension within the concavity, a propeller shaft passing longitudinally through said concavity, means for operating said shaft, a propeller wheel secured to said shaft within 105 the concavity, and additional bracing means for said keel extension having journal boxes for the reception of the propeller shaft, said additional bracing means being provided with means for admitting a lubricant to the 110 shaft bearings carried thereby.

In testimony whereof I affix my signature in presence of two witnesses.

GEORGE WASHINGTON WATTS.
